W. A. DUNN

ELECTRIC WIRING SYSTEM AND APPARATUS

Filed March 27, 1922

Ward A. Dunn
INVENTOR

BY *J. M. Thomas*

ATTORNEY

UNITED STATES PATENT OFFICE.

WARD A. DUNN, OF OGDEN, UTAH.

ELECTRIC WIRING SYSTEM AND APPARATUS.

Application filed March 27, 1922. Serial No. 546,978.

To all whom it may concern:

Be it known that I, WARD A. DUNN, a citizen of the United States, residing at Ogden, in the county of Weber and State 5 of Utah, have invented certain new and useful Improvements in Electric Wiring Systems and Apparatus, of which the following is a specification.

My invention relates to electric motors 10 and has for its object to provide a safety device to prevent the burning out of an electric motor while in operation of either the two-phase or three-phase type should any one of the four main fuses of the two- 15 phase type or any one of the three main fuses of the three-phase type be burned out, leaving the motor operating on the other phase or phases, and particularly to provide an auxiliary fuse for each main fuse and 20 which auxiliary fuses are connected in series with the under voltage release circuit, whereby the release circuit is broken before any injury may occur to the motor, thus releasing the main motor circuit contacts 25 of the auto starter, compensator or switch.

These objects I accomplish with the device and wiring connected therewith which is illustrated in the accompanying drawings in which similar letters and numerals of 30 reference indicate like parts throughout the several views and as described in the specification forming a part of this application and pointed out in the appended claim.

In the drawings in which I have shown 35 a substantial embodiment of my invention Figure 1 is a diagrammatic view showing the electric circuits and parts of the apparatus as applied on a three-phase motor. Figure 2 is a similar view as used on a two- 40 phase motor. Figure 3 is an elevation of my auxiliary fuse shown applied to any main motor cartridge fuse, parts shown in section. Figure 4 is a plan view showing the bottom of the auxiliary fuse applied 45 to any main motor cartridge fuse, with parts cut away. Figure 5 is a transverse section on line 5-5 Figure 3. Figure 6 is a diametrical longitudinal section of the sockets and wire used to connect the fuses in series, 50 parts cut away.

It is well known that any two-phase or three-phase motor in operation, unless over loaded, will continue to run on the other phase or phases when from any cause one 55 of the main motor fuses is blown out or destroyed, and injury to the extent of burn-

ing out the motor will result unless the motor is stopped. And it is the main feature of the present invention to use an auxiliary fuse, in conjunction with each and all of the 60 main fuses, to provide a positive method and means for opening the under voltage release circuit, thereby automatically releasing the main motor contacts of the auto-starter, compensator or switch immediately 65 on the blowing of any one of the main fuses. This is accomplished by providing a low amperage auxiliary fuse in close proximity to and for each of the main fuses, which auxiliary fuse is of sufficient size to only 70 carry the small current of the under voltage release circuit, which low amperage auxiliary fuses are connected in series, and so positioned in relation to the main fuses that when either of the main fuses are blown out, 75 the arc caused by the blowing or burning in two of the main fuses, or the melting and separation of the main fuse, which separated ends or end, while still overheated, will drop down against the adjacent auxiliary low amperage fuse short circuiting 80 the under voltage release circuit, thereby instantly burning said auxiliary fuse in two, thus instantly opening the under voltage release circuit, which immediately operates the under voltage release mechanism 85 and releases the main motor contacts of the auto-starter, compensator or switch before any damage can result.

The present invention consists of a fuse 90 cartridge shell A of cylindrical form within which is a longitudinally disposed main fuse 1 with contact caps B with which said fuse is connected. In the bottom of the cylindrical wall of said shell A are inserted 95 two auxiliary fuse cases C at practically right angles to said shell A, with a portion of the inner ends cut away as at 2. An auxiliary fuse 4 is positioned centrally in each of said cases C and then bent at right 100 angles and run parallel with said main fuse from one of said cases C to the other. The said auxiliary fuses are of light amperage, as they are intended to only carry the current required to operate the under voltage 105 release mechanism and are to be burned in two by the arc produced by the blowing or burning in two of the main motor fuse 1, or this failing to break the auxiliary fuse, the remaining burned and overheated ends of 110 the destroyed main fuse dropping down against said auxiliary fuse thereby short

2

circuiting the under voltage release circuit, causing the auxiliary fuse to instantly burn in two, thus opening the under voltage release circuit, which in turn releases the main 5 motor circuit contacts of the auto-starter, compensator or switch, if the main fuse 1 should burn out at any time while the motor is running under normal or greater load. A connection is made between said auxiliary 10 fuse terminals by the wire 5, the ends of which are secured in the sockets D, which sockets are to be pushed over the external ends of said cases C, making contact with terminal of fuse 4, but any form of connection 15 may be used between said terminals of fuses 4, to place them in series. Any form of connection may then be used to connect one terminal end of the series composed of fuses 4 to one main motor circuit 20 wire; this connection to said motor circuit wire to be made between the main fuses and the auto-starter, compensator or switch. The under voltage release circuit is then completed through the series of fuses 4, by 25 connecting the remaining terminal of said series of fuses 4 through the overload relay (if one is used), thence through the under voltage release in series, thence back into one of the other main motor circuit wires, 30 connection with said wire to be made between main motor fuses and auto-starter, compensator or switch.

The operation of my system of connecting the wires and using my apparatus is as follows:

The auxiliary fuses are parallel with and in close proximity with the main fuses for motors of the class described, and said auxiliary fuses are connected in series, and the auxiliary fuses are connected with the under voltage release coil of the auto-starter, compensator or switch, in order that should any one of the main fuses 1 be blown out, the arc of the main fuse at the instant it blows or by one or both remaining ends of the main fuse dropping against the auxiliary fuse causing a short circuit in the under voltage release circuit, thereby causing the auxiliary fuse to be burned in two and opening the under voltage release circuit.

Having thus described my system of wiring and the apparatus by which it may be carried out, I desire to secure by Letters Patent and claim:—

An apparatus for protecting a multiple-phase motor comprising a cartridge fuse shell, of a main fuse carried in said shell; two auxiliary fuse cases in the side wall of said shell; a fuse of less amperage connected with said cases and carried in said shell 55 parallel with said main fuse.

In testimony whereof I have affixed my signature.

WARD A. DUNN.
